ATTY'S.

UNITED STATES PATENT OFFICE.

PETER GAVIN, OF KAMLOOPS, BRITISH COLUMBIA, CANADA.

EXCAVATOR.

1,180,288.

Specification of Letters Patent. Patented Apr. 25, 1916.

Application filed May 6, 1915. Serial No. 26,410.

To all whom it may concern:

Be it known that I, PETER GAVIN, a subject of the King of Great Britain, and resident of the city of Kamloops, in the county 5 of Yale, in the Province of British Columbia, Dominion of Canada, have invented certain new and useful Improvements in Excavators, of which the following is the specification.

10 This invention relates to excavators particularly adapted for use in placer mines, subaqueous and similar constructional operations.

15 The object of the invention is to provide means for automatically securing and releasing a shovel carrying carriage to and from a suspended cable prior to and after dumping all the excavated material in the shovel.

20 The invention also has other objects such as the facilitating of digging into the material to be moved; of refinement of parts so that the device may be easily assembled, adjusted and taken apart for shipment; besides the simplification and cheapening of 25 the construction generally.

With the above objects in view, the invention consists essentially of the improved construction particularly described and set 30 forth in the following specification and accompanying drawings forming part of the same.

In the drawings, Figure 1 is a side elevation of the suspended carriage with the 35 excavating shovel mounted thereon in a position ready for dumping. Fig. 2 is a side elevation of the suspended carriage with the excavating shovel mounted thereon discharging its load. Fig. 3 is a perspective 40 view of the suspended carriage, broken away, with the automatic trip device mounted thereon.

Like characters of reference refer to like parts in the several drawings.

45 Referring to the drawings, A represents the improved excavator comprising the inclined aerial cable g carrying the carriage h to which the upper ends of the straps x rigidly mounted on the rear end of the shovel C 50 are pivotally mounted. The ends of the inclined cable are adjustably secured to transversely extending ropes or the like i and j, stretched between the supporting posts or trees k and l located adjacent to the 55 excavation and dumping bank respectively.

The carriage is designed to travel on the

inclined cable g and to this end is provided with brackets m carrying rotatably mounted pulleys n adapted to ride thereon while to obviate any tendency of the said carriage jumping the cable I preferably provide idler pulleys o rotatably mounted on the brackets and designed to engage the lower side of the cable diametrically opposite the first said pulleys. 60

65 Mounted on the lateral faces of the carriage h near the front end thereof are brackets p adapted to house the pulleys E rotatably mounted on the transversely extending spindle q which further engages intermediate of its length the lower end of the V-shaped frame a, the upper end of which carries the pivotally mounted gravity detents or claws b, the object of which will be made clear hereafter. 70

75 The frame a further carries intermediate of its ends the striking lever f pivotally mounted on the spindle 2 and having an offset upper end pivotally engaging the pin 3 mounted in the lower end of the T-shaped striking lever e which is pivotally mounted intermediate of its length on the pin 4. The transverse member of the T-shaped striking lever e coacts with the upper end of the gravity detents or claws b. 80

85 The operation of the shovel is controlled by the hauling rope r carrying on one end a shackle F adapted to engage the flexible bridle s intermediate of its ends, which bridle takes around the pulleys E and is secured at the ends to the upper offset ends of the angularly disposed braces t mounted on the shovel, the said bridle being further provided with a striking bar e rigidly mounted thereon. 90

95 To facilitate in the excavating I provide a plurality of pointed fingers D rigidly mounted on the bottom of the shovel and braced to the back thereof.

Coacting with the striking lever f is an 100 adjustable stop member u mounted on the inclined cable g above the dumping bank, such member being preferably made in two portions having a conical head d and an integral shank w adapted to be secured by 105 bolts or the like, to embrace the said cable and be frictionally retained thereon in any desired position.

110 In the operation of the excavator the inclined cable g is lowered through the medium of block and tackle to permit of the shovel C resting on the material to be excavated.

whereupon when the hauling rope *r* is pulled taut the fingers *D* assist the front of the shovel in digging into the material and filling the shovel. The inclined cable is then 5 adjusted and the carriage *h* carrying the shovel *C* drawn up the same to the dumping bank when the detents *b* impinge on the conical head *d* of the stop member *u* rotating the detents *b* which fall under the action of 10 gravity to embrace the shank *w* and engage the back face of the said conical head so anchoring the carriage in position, whereupon the hauling rope *r* is slackened off to allow the shovel to rotate in a vertical plane 15 under the action of gravity and deposit its load.

Just as the dumping process has been completed and the shovel *C* hangs in a substantially lowered position, the striking member 20 *e* carried by the bridle *s* impinges on the striking lever *f* rotating the same and disengaging the T-shaped lever *c* from the detents *b* which then rotate to clear the conical head *d* of the stop member, the hauling rope 25 *r* being then paid out to permit of the carriage *h* returning to the excavation for the refilling of the shovel.

It will be clear that although the carriage *h* and the pivotally mounted shovel *C* carried thereby are free to return to the excavation under the action of gravity they are at 30 all times under the control of the hauling rope *r* which is in turn controlled by any suitable type of motive or hauling power 35 capable of being advantageously applied thereto.

It will be understood that any type of motive or hauling power may be advantageously applied to the hauling rope *r*.

40 By forming the fingers *D* in the manner stated, a cushioning effect is given to the shovel *C* when it is lowered primary to excavating, and at the same time the rear of the shovel is slightly raised so that the 45 points of the fingers are better able to dig into the material being excavated.

As many changes could be made in the above construction and many apparently 50 widely different embodiments of my invention, within the scope of the claims, con-

structed without departing from the spirit or scope thereof, it is intended that all matter contained in the accompanying specification and drawings shall be interpreted as illustrative and not in a limiting sense.

55

What I claim as my invention is:

1. An excavator of the class described comprising an inclined aerial cable, a carriage mounted thereon, a gravity operated shovel pivotally mounted to the carriage, a 60 V-shaped frame pivotally carried by the carriage, claws pivotally mounted on the V-shaped frame and a conically headed stop member on the inclined cable adapted to 65 coact with the claws, substantially as described.

2. An excavator of the class described comprising an inclined aerial cable, a carriage mounted thereon, a shovel pivotally mounted to the carriage, pulleys pivotally 70 mounted on the sides of the carriage near the front thereof, a bridle engaging with the pulleys and secured to the front end of the shovel, a hauling rope attached to the bridle, a V-shaped frame mounted on the carriage, 75 gravity detents mounted in the upper end of the V-shaped frame, a striking member on the bridle, a striking lever pivotally mounted on the V-shaped frame, a pivotally mounted T-shaped lever on the V-shaped 80 frame operated by the striking lever, and a stop member on the inclined cable engaging with the said detents.

3. An excavator of the class described comprising an inclined aerial cable, a carriage supported therefrom, a shovel pivotally mounted to the carriage, an adjustable stop member mounted in the cable, gravity claws operatively supported from the carriage adapted to coact with the stop member, a pivotally supported T-shaped lever 90 coacting with the claws, and means for rotating the lever simultaneously with the dumping of the shovel.

In witness whereof I have hereunto set 95 my hand in the presence of two witnesses.

PETER GAVIN.
